DESIGN FOR AN ADVERTISING CLOCK

Harry Yonofsky and Harold Thorstensen,
Brooklyn, N. Y.

Application October 31, 1938, Serial No. 80,791

Term of patent 7 years

To all whom it may concern:

Be it known that, Harry Yonofsky and Harold Thorstensen, citizens of the United States of America, residing at Brooklyn, in the county of Kings and State of New York, have invented a new, original, and ornamental Design for an Advertising Clock, of which the following is a specification; reference being had to the accompanying drawing, forming part thereof.

Figure 1 is a front elevational view of an advertising clock, showing our new design;

Figure 2 is a top plan view; and

Figure 3 is a side elevational view of the same.

We claim:

The ornamental design for an advertising clock, as shown.

HARRY YONOFSKY.

HAROLD THORSTENSEN.
